UNITED STATES PATENT OFFICE.

RUSSELL H. BENNETT, OF TUCSON, ARIZONA.

RAIL PANTOGRAPH.

1,418,614.

Specification of Letters Patent. Patented June 6, 1922.

Application filed March 2, 1920. Serial No. 362,754.

To all whom it may concern:

Be it known that I, RUSSELL H. BENNETT, a citizen of the United States, residing at Tucson, county of Pima, and State of Arizona, have invented a certain new and useful Rail Pantograph, of which the following is a specification.

This invention relates to an instrument for making mechanically a drawing or diagram of an object, and it has especial reference to a polar pantograph for recording upon a flat surface the true and accurate profile, outline or contour particularly of a rail, with the end in view of ascertaining from such drawing the condition of the rail and thereby determining its fitness for further use.

One of the main objects of this invention is to provide a simple means for accomplishing this purpose, in which the delineation of the object may be recorded graphically with ease and rapidity and which may be quickly attached to and removed from the object.

Other objects will appear from the subjoined specification in connection with the accompanying drawing, showing a preferred form of the invention, and in which—

Fig. 1 is a front view showing the invention as applied.

Fig. 2 is a side view partly in section.

The invention, generically considered, comprises a rail engaging member and an instrument associated therewith, comprising a tracer and a marker.

Specifically the invention may comprise a clamp 1, consisting of two legs 2 and 3, the lower ends of which are inwardly bent and constitute substantially a rail-web-engaging jaw, co-operating with two plates 6 and 7, respectively fastened at one side to the front and back of said legs 2 and 3, and each plate 6 and 7 formed in its free end with a curving recess 8 and 9, arranged for engagement with a pin 10 and 11, on the front and back, respectively, of each leg,

securely to conjoin the two legs and form a substantial support for the clamp when applied to a rail. The lower edges of the plates 6 and 7, as seen, lie or rest upon the highest portion of the rail head regardless of its shape or condition of its wear and, co-operating with the jaw portion of the legs, maintains the clamp in upright position or at an accurate right angle to the horizontal plane of the rail head. These plates also serve to bring together the two legs when

applying the clamp, the weight thereof causing the plates to move toward each other, consequently drawing together the legs, preparatory to their being locked in position, as explained hereinafter.

The legs 2 and 3 are connected by spacers 12 and 13 on the back and front of the clamp and upon these spacers the legs fulcrum.

The upper extremity of the legs 2 and 3 is pivotally connected by a toggle arrangement 14, controllable by a handle 15 for operating the legs about the fulcrums when placing the clamp upon or removing the same from a rail. To one of the legs, say 3, may be fastened a carrier plate or holder 16, for a card or other article 17, upon which the diagram of the rail head is to be traced.

Associated with the clamp 1, is a tracing and marking device or frame, which may comprise a stylus 18, adjustably carried in a yoke or bracket 19, swiveled on the end of a slotted bar 20, that is movable relatively to a central guide and pivot pin 21, centrally provided in the spacers 12 and 13. The movement of the stylus 18 along the profile or outline of an object is recorded upon the card 17 by means of a pencil 22 or other drawing or inscribing means, firmly held in the end of a complementary slotted bar 23, also movable relatively to the central guide and pivot pin 21, the two bars 20 and 23 being interconnected and held in perfect alinement by an expandable means, as lazy tongs 24, pivotally attached at its respective ends to said bars 20 and 23, and centrally supported upon such pivot pin 21, about which the entire tracing and marking frame may be swung and operated during the process of making a diagram.

Assuming that the object selected be a rail 25, the stylus 18 and pencil 17 are grasped by the hands of the operator and the stylus moved about that portion of the rail desired to be outlined, while the recordation is made simultaneously upon the card 17. On account of the irregularity and changing planes of the object, the stylus is adjustable to enable the point thereof to follow closely all surfaces, and hence, when for instance the under- and outside of the rail head have been traversed, the stylus is turned to bring the apex thereof upon the tread, and this is accomplished by manipulation of the knurled nut 26 screwed or otherwise connected with the shank of the stylus.

When the record is made, the device may be quickly and readily removed by lifting up the handle 15, which, operating the toggle joint 14, causes the legs 2 and 3 to be moved 5 about their fulcrum and the ends 4 and 5 to be moved away from each other.

When applying the clamp to a rail, the handle 15 is pressed until the connected toggles pass their central axis, at which time 10 the handle 15, engaging the upper inner ends of the legs 2 and 3, maintains the legs in rigid locked position upon the object.

What I claim, is:—

1. In a device for making outlines of an 15 object, a clamp comprising pivoted jaws adapted to embrace said object, means securing the upper ends of said jaws whereby the clamp may be lifted, said means expanding said jaws upon lifting the clamp there- 20 with and contracting said jaws upon the arrest of movement of said clamp by said object, means on one of said jaws for arresting movement of and supporting the clamp on engagement with said object, and a tracing

and marking mechanism mounted on said 25 clamp.

2. In a device for making outlines of an object, a clamp comprising jaws connected to each other by pivotal means intermediate their ends, a handle toggle connecting cor- 30 responding ends of the jaws, means on one of said jaws for arresting movement of and supporting the clamp on engagement with said object, and a tracing and marking mech- 35 anism mounted on said clamp.

3. A device for making outlines of an object comprising two members inwardly bent at one end, plates secured to said members and co-operating with said ends to form a clamping jaw, means connecting and for 40 pivoting said members, means to operate said members about their pivots, and an ex- pansible frame pivotally mounted on said 45 connecting means, and provided at one end with a stylus and at the other end with a marker.

In testimony whereof I have set my hand.

RUSSELL H. BENNETT.
